UNITED STATES PATENT OFFICE.

HENRY D. HERRINGTON, OF HOOSIC, NEW YORK.

POTATO-PLANTER.

SPECIFICATION forming part of Letters Patent No. 288,287, dated November 13, 1883.

Application filed June 8, 1883. (No model.)

To all whom it may concern:

Be it known that I, HENRY D. HERRINGTON, a resident of the town of Hoosic, in the county of Rensselaer and State of New York, have invented certain new and useful Improvements in Potato-Planters; and I do hereby declare that the following is a full, clear, and exact description of the invention, that will enable others skilled in the art to which it appertains to make and use the same, reference being had to the accompanying drawings, and to the letters of reference marked thereon, which form a part of this specification.

Similar letters refer to similar parts in the several figures therein.

My invention relates to improvements in potato-planters of that class employing a hopper provided with a suitable platform, to which the potatoes are fed from the hopper, and from which they are dropped into a receptacle connecting with a spout and delivered from the latter into a furrow in the ground just back of the furrow-opener, where they are covered by suitable followers. In my invention the hopper is provided with suitable mechanism for supplying the platform with potatoes, and the spouts are provided with suitable valves at their upper and lower ends, which are automatically opened and closed to drop the potatoes in hills at a regular distance apart. The mechanism is operated by suitable gearing connected with traction-wheels. The hopper is also provided with suitable means for regulating the number of potatoes delivered upon the platform.

The objects of my invention are, first, to provide a certain and rapid means of dropping and covering potatoes in hills and rows in such a manner that the hills and rows shall be separated from each other by a uniform distance; second, to provide a suitable device for stamping the earth which covers each hill.

Figure 1, Sheet 1, is a front elevation of a portion of my improved planter. Fig. 2, Sheet 2, is a side elevation of same. Fig. 3, Sheet 3, is a side elevation of a part, and a vertical section of the hopper and platform, taken at the broken line $x-y$ in Fig. 4, Sheet 3. Fig. 4, Sheet 3, is a plan view of the hopper and platform.

A and A' represent the traction-wheels,

fixed to revolve with the axle B and gear-wheel C, fixed on said axle. Gear C engages with pinion D to revolve shaft E. Frame H is provided with suitable bearings for axle B, 55 and supports the various mechanisms. Shaft E is provided with chain-wheel N, adapted through chain C' to revolve chain-wheels M and M', Fig. 2. Chain-wheels M M' are each fixed upon and revolve a crank-shaft, I J J', 60 one of said crank-shafts being shown in Fig. 1. Said crank-shafts are connected with the agitator K—one at each end. The agitator is provided with four sets of teeth, t, which pass up along and down through openings or slits L' in 65 the bottom of the hopper F and platform V as the crank-shaft revolves, this revolution being such as to cause the teeth to travel in a direction from the hopper toward the platform when they are projected up through said bottom openings 70 in the position shown by dotted lines in Fig. 3, Sheet 3. The potatoes which are deposited in hopper F F' are thus gradually forced by the action of the agitator upon them from the hopper out onto the platform. The quantity 75 thus delivered upon the platform can be regulated by the lever O, connected by wire o with the movable board or bottom L, as shown, one end of L being hinged to the frame or loosely fastened by a screw, as shown in Figs. 80 3 and 4. If the potatoes are delivered too fast, L is raised by the lever, which lifts the potatoes up beyond the reach of teeth t, or sufficiently to retard their speed of delivery upon the platform. As the potatoes are delivered upon the platform, an attendant sitting 85 upon the seat S' selects the desired number for a hill and deposits it or them in the box T', the bottom of which opens into the spout T. There may be any desired number of spouts— 90 one for each row to be planted. I have shown two, with which two rows of potatoes may be planted at the same time. The box T' is provided with the horizontally-sliding valve d', Fig. 2, connected with one end of the lever 95 b, fulcrumed upon the fixed arm e. The other end of lever b is acted upon by pin a, Fig. 1, projecting from one side of wheel y, fixed to revolve upon shaft E, from which it appears that each revolution of shaft E operates to withdraw valve d' from box T' and allow the potatoes deposited therein to drop down to the

lower end of the spout. The lower end of the spout is provided with the hinged cover *d*, having the arm *e*, to the projecting end of which is attached the cord *h*, passing over 5 pulley *p*, and connected at the other end with lever *b*, as shown in Fig. 2, which acts to open cover or valve *d* at the same time that valve *d'* is opened. The valves are closed again by the spring *g*, which reacts upon arm *e*, and 10 through cord *h* pulls lever *b* back to its normal position, at the same time forcing valve *d'* back into box *T'*. When the attendant has deposited a potato in box *T'*, the operation of the machine is as follows: At the proper place 15 for a hill of potatoes the valves are both opened by the mechanism described and the potato falls to the bottom of the spout; but the valves have closed again before the potato reaches the bottom, and it is held at the mouth of the 20 spout upon the cover until the valves are again opened, when the potato at the mouth of the spout falls out upon the ground and another falls from valve *d'* to take its place, from which it appears that the potatoes are certain 25 to be dropped at regular intervals, provided only that the attendant deposits a potato upon the slide *d'* at any time before it opens.

The furrow-opener *W* prepares a place in the ground to receive the potatoes, the depth 30 of which may be varied by varying the height of the opener relatively to the traction-wheels *A A'*. The potatoes are then covered by the followers *x*—one on each side of the furrow, and inclined to fill the furrow again. The furrow- 35 openers and followers may be raised up from the ground, when not in use, by means of the lever-handle *U*, attached to shaft *u*, provided with arm *c'*, and chain or cable *b'*, attached to arm *l*, fixed upon the frame which supports 40 the furrow-opener. The opener-frame is thus lifted up against the frame which supports the followers, and then takes the latter with it up against or near the axle *B*, both frames being connected with pole *n* by the arms *t* 45 and *t'*.

w is the whiffletree-evener, attached to pole *n*, and *w'* a foot-rest for the driver who sits upon the hopper *F*, any suitable seat being provided thereon.

50 *Q* represents the stamper, attached to the upright *q*, the latter being pivoted to the lever *R*, which is fulcrumed upon the standard *r*, and so arranged relatively to wheel *S*, fixed

upon shaft *E*, and provided with the semicircular flange *s*, that as the shaft and wheel revolve the flange will strike the short arm of the lever and raise stamper *Q*, and hold it suspended until the flange has passed by the lever, when the stamper will fall by its own weight upon the ground, stamping down the earth 60 and marking the place of the hill of potatoes; or it may be forced down by a spring. By means of a set-screw the angular position of the flanged wheel on the shaft can be varied to adjust or readjust the action of the stamper 65 relatively to that of the other parts of the machine. The upright *q* moves between projecting arms *q'* to guide it in its course, and the spring *s'* causes it to return to a vertical position after passing over any obstruction which 70 might throw the stamper back from the machine. The stamper may be adjusted to rise to different heights by means of different pivot-holes, as shown. The stamper may be used with a corn-planter or any other seed-planter. 75 Flexible spouts may be used and connected with the furrow-openers.

What I claim as new, and desire to secure by Letters Patent, is—

1. In a potato-planter, the combination of 80 a platform for receiving and supporting potatoes, a valved receptacle opening into a double-valved spout, and suitable mechanism for operating the valves in said receptacle and spout, substantially as described, and for the purposes set forth.

2. In a potato or similar planter, the combination, with a conducting-spout provided with upper and lower valves, of the cable *h*, pulley *p*, lever *b*, and means for actuating the 90 lever to which the connecting means of the valves are attached, substantially as and for the purpose set forth.

3. The combination of potato-hopper *F F'*, platform *V*, agitator *K*, regulator *L*, conducting-spouts *T T'*, with their upper and lower valves, and suitable mechanism for operating said parts, substantially as described, and for the purposes set forth.

In testimony whereof I have hereunto set my hand this 5th day of June, 1883.

HENRY D. HERRINGTON.
